UNITED STATES PATENT OFFICE.

WILLIAM W. KITCH, OF CRESTLINE, OHIO.

IMPROVEMENT IN MODE OF ORNAMENTING HARNESS.

Specification forming part of Letters Patent No. 123,709, dated February 13, 1872.

To all whom it may concern:

Be it known that I, WILLIAM W. KITCH, of Crestline, in the county of Crawford and State of Ohio, have invented certain new and useful Improvements in dies for Forming Raised Work on Harness, of which the following is a full, clear, and exact description, reference being had to the accompanying drawing and the letters of reference marked thereon making part of this specification, in which—

Figure 1 is a plan view of a female die. Fig. 2 is a plan view of the male die. Fig. 3 is a vertical sectional view of the dies and leather when the raised work is being formed. Fig. 4 is a vertical sectional view of the raised work when attached to the leather. Fig. 5 is a plan view of the raised work.

The nature of my invention, which is a new article of manufacture, consists in stamping, by the use of male and female dies, any desired design, such as is now represented on the raised work of the harness, on an independent strip of leather. The advantages of the invention consist in furnishing the means whereby a harness can be most elaborately and elegantly finished at a most trifling expense.

The construction and operation of my invention is as follows: A and B represent an ordinary male and female die. The desired design is cut in each die—on B, being countersunk, and on A, being raised. C is a strip of leather, and, after being suitably softened by moisture, to be easily manipulated, is placed between the dies, and they are brought together by any suitable clamping device. So soon as the strip C receives the desired impression it is removed and its border trimmed off. The strip is then in condition to be tacked or stitched onto any portion of the harness which it may be desired to ornament.

What I claim as new, and desire to secure by Letters Patent of the United States, is—

As a new article of manufacture, the strips C, stamped by dies to represent any desired design for the raised work of harness, substantially as described.

In testimony whereof I have signed my name to this specification in the presence of two subscribing witnesses.
